UNITED STATES PATENT OFFICE.

THOMAS L. STURTEVANT, OF QUINCY, AND THOMAS J. STURTEVANT, OF WELLESLEY, MASSACHUSETTS.

REVERSING MECHANISM FOR EXPLOSION-ENGINES.

SPECIFICATION forming part of Letters Patent No. 790,856, dated May 23, 1905.

Application filed June 11, 1903. Serial No. 160,996.

To all whom it may concern:

Be it known that we, THOMAS L. STURTEVANT, residing at Quincy, and THOMAS J. STURTEVANT, residing at Wellesley, in the county of Norfolk and State of Massachusetts, citizens of the United States, have invented certain new and useful Improvements in Reversing Mechanism for Explosion-Engines, of which the following is a specification, reference being had therein to the accompanying drawings.

This invention has for its object to provide a simple mechanism whereby the direction of rotation of an explosion-engine may be reversed when desired. It is well known to those familiar with this class of engines that when the electric current is shut off for the purpose of stopping the engine the engine will stop on a compression-stroke, for the reason that the power required for compressing the explosive gases in an engine-cylinder is so great that the engine comes to a halt on such a compression-stroke and immediately thereafter a rebound or slight reversal of the engine occurs, due to the elasticity of the compressed charge. Now if an explosive mixture in the cylinder of the engine be fired at the moment the rebound occurs the engine will get a powerful impulse in the reverse direction of rotation commencing with the rebound, so that the engine will continue to run in such reverse direction when the sparking and exhaust devices are properly adjusted.

This invention therefore comprises means whereby an explosive charge will be automatically ignited during the rebound occurring when stopping the engine, thereby reversing the engine.

In carrying our invention into effect we preferably employ manually-controlled means for changing the timing of the sparking and exhaust cams and simultaneously therewith for opening the switch to break the electric circuit and for placing such switch in such position that it will automatically close the circuit and ignite the charge at the rebound occurring after the engine is stopped on a compression-charge.

In the accompanying drawings, Figure 1 is 50 a plan view of a four-cycle four-cylinder explosion-engine embodying our invention. Fig. 2 is a side view of the same, partly in vertical section. Figs. 3 and 4 are sectional detail views, to be hereinafter referred to, 55 showing the sparking and exhaust cams, the switch, and portions of the reversing mechanism. Figs. 5 and 6 are detail views illustrative of the sparking cams and the means for adjusting same. Figs. 7 and 8 are views 60 showing the reversing-switch device in different positions, these views illustrating said switch device as the same appears when looking at it in the direction denoted by the arrow 2 in Fig. 1. Fig. 9 is a detail view 65 illustrative of the gearing and its connection with the secondary shaft. Fig. 10 is a detail view illustrating a portion of the exhaust mechanism.

Referring to the drawings, 12 denotes the 70 main shaft of the engine provided, as usual, with a balance-wheel 13 and having suitable cranks connected by pitmen 15 with pistons 16 in suitable oppositely-arranged cylinders 17, one of which is shown in section in Fig. 2. 75 The explosion-engine herein shown is therefore of a four-cylinder type and is also of a four-cycle type in that an explosive charge in each cylinder is fired at each alternate reciprocation of each piston. Each cylinder is 80 provided with an inlet-valve 18 and an exhaust-valve 19, the exhaust-valve being held to their seats by suitable springs, and the explosive gases are in the present machine preferably fired by jump-spark devices 20, connected in suitable electric circuits (indicated by the wiring in Fig. 2) and supplied from a suitable source of electricity, as from a dynamo or from a battery 21. The several circuits referred to are in the present instance 90 connected with a jump-spark-coil box 23, containing tremblers of well-known construction, such as are usually employed in jump-spark circuits; but any suitable means for supplying an interrupted or other kind of 95 current may be employed.

The main shaft 12 is provided with a spiral gear-wheel 24, meshing with a smaller spiral

gear 25, mounted on a secondary shaft 26, rotating at half the speed of the main shaft. Splined to the secondary shaft 26 to rotate therewith are the exhaust-cams 27 for operating the levers 28, engaging the upper ends of the exhaust-valve rods 29. The shaft 26 is adapted to be shifted endwise in its bearings and is provided with a roller-stud 30, entering a spiral slot 31, formed in a sleeve 32, and to which sleeve the spiral gear 25 is rigidly attached. The sleeve 32 is held from endwise movement with the shaft 26 between suitable bearings 33, and owing to the fact that the gear-wheel 25 is in mesh with the larger gear-wheel 24, so that said gear-wheel 25 will be held from relative movement, it results that when the shaft 26 is moved endwise the spiral slot 31 in the collar 32 will cause a relative turning movement of said shaft 26 and of the exhaust-cams 27, splined thereto, so that an endwise movement of said shaft 26 will cause a change of the timing of said exhaust-cams. The exhaust-cams are restrained from endwise movement with the said shaft by the stationary shaft-bearings contiguous to the ends of said cams. (See Figs. 3 and 4.) The shaft 26 is also provided with a pin or roller-stud 34, entering a spiral slot 35 in a sleeve 36, to which are secured the sparking cams 37 for closing the several circuits at the proper times to effect the firing or igniting of the compressed gases, each of said cams operating a movable contact device or pin 38, which is forced against a stationary contact device or pin 39 when the circuit is to be closed. Thus when the shaft 26 is moved endwise its torsional or turning movement will cause a change of timing of the exhaust-cams 27 and will also change the timing of the sparking cams 37, and the turning or torsional movements of which latter will be different from that of the exhaust-cams owing to the pin and spiral slot connection of sleeve 36 with the said shaft 26. The sleeve 36, to which the sparking cams are fixed, will be held from endwise movement with the said shaft 26 by the box 40, which incloses the sparking cams and their contact devices. In other words, the said box will restrain the said cams from moving endwise with said shaft and the cams being fixed to said sleeve will restrain the latter from endwise movement. (See Fig. 4.) The normal working positions of the sparking cams may be regulated as may be desired by shifting the box 40 to different positions, as indicated in Figs. 5 and 6, and in these different positions of adjustment of the said box 40 it may be fixed in place by means of a slotted sector-post 41 and a nut or hand wheel 42, engaging a stud 70, fixed to said box and entering the slot in said post. The shaft 26 may be moved endwise in any suitable manner, but preferably by a hand-lever 43, having a swiveled connection with said shaft, as

will be understood from Figs. 2 and 3, so that the said shaft may freely rotate, but may be moved endwise either during rotation or when at rest by means of the manually-operated lever 43.

Attached to the shaft 26 are two friction-cones 44, surrounded by a friction-sleeve 45, to which is rigidly connected an arm 46, in which are pivotally mounted two contact devices 47 and 57, the free ends of which are normally pressed apart by a spring 48.

Attached to the frame of the engine is a standard 49, provided with an opening or slot 50, into which the contact devices 47 and 57 extend loosely in such a manner as to have a limited movement vertically. Supported by the standard 49 are contact-pins 51 and 52, carried by springs 53, so as to be capable of more or less vertical movement. The pins 51 and 52 are adapted to be forced into contact with each other by the contact devices 47 and 57, as will be understood from Figs. 7 and 8, when the friction cones and sleeves are in either of the positions denoted in full and dotted lines in Fig. 2. Thus when the said friction cones and sleeves are in the position shown by full lines in Fig. 2 the contact devices 47 and 57 will be in the position denoted in Fig. 7 and the circuit (grounded through the engine) will be closed through the contact-pins 51. When, however, the shaft 26 is moved endwise toward the left, Fig. 2, so as to move the friction cones and sleeve to the position denoted by dotted lines in said figure, the contact devices 47 and 57 will be moved to the right-hand end of the slot 50 with reference to Fig. 8 (or the left-hand end of said slot with reference to Figs. 1, 2, and 3) and the contact device 57 will be brought against the stop 54 on the standard 49, so as to compress the spring 48. In other words, when the engine is running forward and the shaft 26 is rotating in the direction of the arrow in Fig. 3 the contact devices 47 and 57 will be lifted against the upper wall of the slot or opening 50 in the standard 49, owing to the friction between the cones 44 and the sleeve 45, and with which sleeve the contact devices 47 and 57 are connected, and thus if the shaft 26 be shifted endwise toward the left hand, Fig. 2, while the engine is running the said contact devices 47 and 57 will be held against the upper wall of the slot or opening 50 until the engine is reversed at the rebound. This result is due to the friction between the cones 44 and the sleeve 45, which has a tendency to lift the arm 46, which is rigid with said sleeve and on which arm the contact devices or switches 47 and 57 are pivotally mounted. The shifting of the shaft 26 to the left, Figs. 1 and 2, opens the electric circuit, owing to the removal of the contact device 47 from the pin 51, and the sparking device being thus interrupted the engine will soon come to rest and will stop on a compression-stroke.

As the engine thus stops on a compression-stroke the elasticity of the compressed charge will cause a rebound, which would normally be only a slight reversal of the engine; but in accordance with the present invention this rebound is utilized to ignite the compressed charge when the rebound occurs, and thus set the engine running reversely. The first effect of the rebound communicated through the shaft 26, the friction-cones 44 thereon, and the friction-sleeve 45, surrounding said cones, imparts a downward movement to the arm 46, and thereby releases the spring-pressed contact devices 57 from the stop 54, and as soon as said contact device 57 is released from its stop and is moved downward into contact with the lower wall of the slot or opening 50 the spring 48 immediately forces said contact device or switch 57 beneath the contact-pin 52 and closes the circuit, so as to ignite the compressed charge. Thus when a rebound occurs the compressed charge will be automatically ignited at the proper instant after the hand-lever 43 has been moved to shift the shaft 26 endwise, this endwise movement of said shaft changing the timing of the sparking and exhaust cams through the mechanism heretofore described. When it is desired to stop the reverse movement of the engine and set the same running forward, the hand-lever 43 is moved from the position denoted in dotted lines to the position shown in full lines in Fig. 2, thereby moving the friction-cones 44 and friction-sleeve 45 from the position shown in dotted lines to the position shown in full lines in said figure, as the shaft 26 is shifted endwise, such movement of the said hand-lever and of the said shaft 26 moving the switch contact devices 47 and 57 from the position shown in full lines in Fig. 8 to the position partly shown in dotted lines in Fig. 7, with the contact device or switch 47 against the stop 55 at the lower wall of the slot or opening 50, the said contact devices 47 and 57 being, it will be understood, held against the lower wall of said slot or opening 50 so long as the engine is running backward or reversely. This shifting movement of the contact devices or switches 47 and 57 shuts off the sparking-current, so that the engine will stop on a compressed stroke, and in thus stopping will rebound slightly or start to run forward, and such rebounding forward movement of the engine-shaft, communicated through the secondary shaft 26, the friction-cones 44, secured to said shaft, the friction-sleeve 45, engaging said cones, and the arm 46, rigid with said friction-sleeve, will lift the contact devices or switches 47 57, so that the contact device or switch 47 will be clear of the stop 55 and will be forced by the spring 48 beneath the contact-pin 51, thereby again closing the circuit, and as the exhaust and spark-

ing cams will, simultaneously with the shifting movement of the switch by the hand-lever 43, have been returned to their first positions in proper timing for running the engine forward the ignition of the compressed charge, when the circuit is closed through the switch-contact device 47 and pins 51, will again set the engine running forward in the same smooth and easy manner in which it was started running backward. 75

From the foregoing it will be understood that our invention comprises means whereby, when a manually-operated device or lever is moved to shut off the sparking-current for the purpose of stopping the engine, the continued movement of said manually-operated device will set the switch in such position that when the engine-shaft is slightly reversed by the rebound always occurring in this class of engines after the engine has been 80 fully stopped, and which stoppage always occurs on a compression-stroke, the compressed charge will be automatically ignited and the engine be set running in the reverse direction. Thus as the rebound is in itself 85 the commencement of the reversal of the engine, and as the compressed charge is ignited at the rebound, so as to give a powerful impulse or acceleration to the reverse movement of the engine commencing with the rebound, 90 the reversal of the engine is effected without any such sudden shock as would occur if a charge were ignited for the purpose of reversing the engine while the engine was still running forward. Our invention therefore 95 enables us to reverse an explosion-engine and to start the same running in either direction by power in a smooth and easy manner without shock and without straining the machinery. 100 105

Having thus described our invention, we claim and desire to secure by Letters Patent—

1. In an explosion-engine, the combination with a sparking apparatus, of a manually-operated switch by which an electric circuit may be opened to shut off the current, and automatic means, connected with the engine-shaft, whereby the circuit will be closed when a rebound occurs at a compression-stroke, for the purpose of setting the engine running in a reverse direction. 110 115
2. In a four-cycle explosive-engine, the combination with a sparking apparatus, of a manually-operated switch for opening the circuit, and which is so arranged that it may be manually set for automatic closing, and automatic means, connected with the engine-shaft, whereby the circuit will be closed when a rebound occurs at a compression-stroke, for the purpose of setting the engine running in a reverse direction. 120 125
3. In an explosion-engine, the combination with an electric sparking-circuit and a switch for opening and closing the same, of 130

automatic means for closing the circuit, when the current is shut off, at the instant of rebound on a compression-stroke; thereby positively reversing the working of the engine 5 by continuing the reverse movement commenced by the rebound.

4. In an explosion - engine, a reversing mechanism comprising the combination with an electric sparking - circuit and sparking 10 and exhaust cams, of manually-controlled means for changing the timing of said cams, a switch, and automatic means whereby, at the rebound, on a compression-stroke and when the current is shut off, the switch will 15 be caused to close the circuit and ignite the compressed gases; thus positively continuing the reverse movement of the engine commenced by the normal rebound.

5. In an explosion - engine, the combination 20 with an electric sparking apparatus, of manual means for opening the circuit, automatic means, controlled from the rebound of the engine-piston, for closing the circuit and thereby igniting a compressed charge when a 25 rebound occurs after the engine has been stopped, for the purpose of reversing the engine.

6. In an explosion - engine, the combination 30 with an electric sparking apparatus, of a manually-adjustable switch for opening the electric circuit, and automatic means for closing the open circuit to ignite a charge when a rebound occurs on a compression-stroke, as the engine is stopped.

35 7. In an explosion - engine, the combination with the main shaft of the engine, of a longitudinally - movable secondary shaft geared thereto, sparking and exhaust cams mounted on said secondary shaft, a switch 40 also connected with said secondary shaft, means for shifting said secondary shaft lengthwise, means for changing the timing of the said sparking and exhaust cams as the said secondary shaft is shifted lengthwise, 45 and automatic means for closing the circuit on a reversal of the said secondary shaft when

a rebound occurs on a compression-stroke as the engine is stopped when the sparking-current is shut off.

8. In an explosion - engine, the combination 50 with an electric sparking apparatus, and manually-adjustable means for changing the timing of the sparking devices, of a switch device for opening and closing the circuit, and frictionally-operated automatic means 55 for closing the circuit to fire a compressed charge when a rebound occurs after the engine is stopped, thereby setting the engine running in a reverse direction commencing with the rebound.

9. In an explosion - engine, the combination 60 with the main shaft 12, of a secondary shaft 26 geared thereto and mounted for endwise or longitudinal movement, means for imparting a torsional or turning movement 65 to said shaft as it is moved longitudinally, sparking and exhaust cams connected with said shaft but restrained from longitudinal movement therewith, so that turning or torsional movements of said shaft will change 70 the timing of said cams, an electric sparking apparatus comprising an automatic switch carried by a part which is frictionally connected with said shaft, and which is longitudinally movable therewith, and manual 75 means for imparting a longitudinal or endwise movement to said shaft to open the electric circuit; whereby, when the said shaft is shifted longitudinally or endwise manually, the timing of the sparking and 80 exhaust cams will be changed and the automatic switch so set that when a rebound occurs after the engine is stopped the circuit will be automatically closed and the engine set running in a reverse direction. 85

In testimony whereof we affix our signatures in presence of two witnesses.
